UNITED STATES PATENT OFFICE.

JAMES W. BRUNDAGE, OF AKRON, OHIO, ASSIGNOR TO THE MILLER RUBBER COMPANY, OF AKRON, OHIO, A CORPORATION OF OHIO.

BIAS-CUTTING MACHINE.

Application filed May 22, 1925. Serial No. 32,086.

My present invention relates to improvements in machines for cutting continuously travelling sheets of fabric or the like into bias cut strips, and is designed as an improvement upon the machine which forms the subject of an application filed by V. V. Messer on the 28th day of February, 1924, Serial No. 695,727.

The invention aims to provide a machine which will take its supply from a supply roll and will wind the cut strips with an interposed liner into roll form convenient for subsequent use.

The invention further aims to provide means whereby the fabric will be smoothly delivered to the platen roll and prevented from slipping thereon.

Another object is to provide means whereby any slippage of the fabric on the drum will be avoided.

In connection with the feature of winding the cut strips on a fabric liner, I have aimed to provide a construction such that the strips will be applied to the liner with their edges in spaced relation.

I have further aimed to provide apparatus of the character described in which sprocket wheels and chains of the standard type embodying removable and interchangeable links may be used, the cutter carriers being designed to be detachably connected to any of said links and the cutters to be individually adjustable lengthwise of the chain.

With these and other objects in view, which will hereinafter appear, the invention comprises the novel features of construction and arrangement, and combination of parts hereinafter described and particularly defined by the appended claims.

An embodiment of my invention is shown in the accompanying drawings, in which:—

Figure 1 is a side elevation of the machine, and

Figs. 2 to 5 respectively, are detail views showing the improved form of cutter carrier—

Fig. 2 being a side elevation of one of these with a portion of the carrying chain.

Fig. 3 an end view,

Fig. 4 a plan view, and

Fig. 5 a section on line 5—5 of Fig. 4.

Referring by the reference characters to this drawing, the numeral 1 designates a platen roll formed preferably of hardened steel having a smooth and polished periph-

ery around which the rubber coated fabric is passed, and by which it is cut by an endless series of moving cutters travelling lengthwise of the roll and impinging against the surface thereof in the manner described in the aforesaid application, which cutters will be hereinafter referred to in detail. I find that in actual commercial practice it is desirable to supply the rubber coated fabric to the drum in roll form, the fabric being wound up in a roll with an interposed liner. Such roll is indicated at A, the fabric being indicated at A' and the liner at B'. The roll A is carried by what may be termed a spool shaft a' supported in brackets 2 from the main frame of the machine, and movement of the drum in unwinding is restricted or retarded by friction means preferably in the form of a band brake 3. As the fabric is unwound from the drum, the liner is wound onto a liner take-up roll B on a suitable spool shaft b' journaled in brackets 4, which spool shaft may be driven in any suitable manner, preferably by means of a belt 6 passing around a pulley 5 on the spool shaft and capable of slippage therein, which belt may be driven from any suitable part of the machine through connections, as shown.

I find that unless precautions are taken to the contrary, there is a tendency of the fabric to wrinkle in passing to the cutting roll, and also to become displaced on the cutting roll, which interferes with the accurate cutting of the fabric. To this end I lead the fabric from the supply roll over a spreader roll 30 which is arranged with helical corrugations extending in opposite directions from the center of the roll toward the ends thereof. From the spreader roll 30 the fabric passes to a puller roll 31 which is located preferably to the left of a vertical plane, Fig. 1, passing through the axis of shaft 8 of the platen roll, the fabric being led back around the platen roll, which causes it to hug the platen roll for not less than one-half the circumference thereof, and this large area of contact prevents any tendency of slippage of the fabric on the platen roll.

I find that the best results are secured by driving the puller roll at a speed about three per cent slower than the platen roll 1, whereby the fabric is laid on the platen roll under tension, and driving the spreader roll 30 slightly faster than the puller roll, the surface of the spreader roll having a slip-

page on the fabric and serving to spread it laterally and smooth it out before it reaches the puller roll. The driving connections for the rolls 30 and 31 may be of any desired type, and are shown conventionally in the drawings.

I find that rubber coated fabric is frequently so sticky or tacky that it tends to stick to the puller and platen rolls, and to avoid this I provide means for brushing the opposite faces of the fabric. A convenient arrangement for this purpose is to provide a pair of arms 53 articulated on the shaft of the spreader roll at each end thereof, which are provided with means tending to rock them in the direction of the arrow, Fig. 1, such for example as weight 54. Articulated on the opposite ends of the levers 53, at 52, are brush carrying levers 50 which have offset arms lying in planes respectively on opposite sides of the plane of the fabric sheet, as indicated at 50^a, which arms are connected respectively by oppositely faced brushes 51 which impinge against opposite faces of the sheet. Springs 55 connected to levers 50 resist the upward motion of the lowermost arms 50^a and hence tend to rock the lever arms 50 about axis 52 to press the brushes with sufficient force against the opposite faces of the sheet.

Shaft 8 of the platen roll carries fast thereon a sprocket 9 which is preferably driven by a sprocket chain 10 passing around sprocket wheels 11, 12, 13 and 14, respectively. The shaft of sprocket wheel 12 may conveniently be used as a source of power for driving the belt 6 through the sprocket connections shown. Sprocket wheel 13 is preferably used for connection to the prime mover which may be effected by suitable worm gearing connections, as shown, to the pulley 17, which latter may be driven by a belt, not shown, from any suitable source of power.

The endless chain of cutters is preferably driven from the shaft 16 of the worm 15 by means of gear 18 on shaft 16 meshing with gear 19 on shaft 20, which shaft 20 carries a gear 21 meshing with a gear 22 on shaft 23, which in turn, through gears 24 and 25, drives shaft 26 carrying gear 27 which meshes with a gear 28 on the shaft 28^a which carries one of the sprocket wheels 28 located at one end of the roll, a similar idle sprocket being provided at the opposite end.

An idle presser roll 32 is arranged to bear against the under surface of the platen roll in close proximity to the platen, to clamp the fabric thereto close to the cutting point, the idle roll being mounted on a swinging frame 33 having an arm extension 34 which is pressed under the tension of a spring 35, which tends to hold the roll 32 pressed towards the platen roll.

I find that in order to expeditiously handle

the cut strips, these should be wound up on a liner with their edges in spaced relation. To this end I provide means for supporting a liner roll C which may comprise brackets 37 carried by the main frame for removably supporting the roller spool shaft, means being provided for regulating the unwinding action of the liner, indicated at C', which regulating means may consist of a friction brake 38. After leaving the liner roll, the liner passes around a roll 36 located adjacent the cutting point but on the opposite side of the cutters from roll 32, such roll 36 being journaled in a swing frame 36^a having an arm or arms 36^b which are pressed under the tension of a spring 36^c whereby the roll 36 is pressed yieldingly towards the platen roll.

Roll 36 is preferably driven by sprocket gearing, as shown, from shaft 14, which in turn is driven by the sprocket chain 10 in the manner hereinbefore described. The swing frame 36^a is mounted to pivot about the shaft 14, the liner travelling around roll 36 and being pressed thereby against the tacky surface of the cut sheets, picks or strips these off from the surface of the platen roll 1 and conveys the said cut sheets to the wind-up roll indicated at D, which is formed as a floating spool supported in the guides 40^a of a bracket 40 carried by the main frame. This take up roll D contacts with drive roll 41 driven by chain and sprocket connections 42, 43, 44, 45 and 46, from the shaft of puller roll 31. The roll 36 is driven somewhat faster (say three percent) than is the platen roll 1, and consequently the cut sections of the fabric are deposited on the liner in spaced relation.

In order to use for the cutters, chain and sprockets of standard construction, I provide the cutter carrying mechanism shown in detail in Figs. 2 to 5 inclusive. In this, 60 designates the chain links which are detachably connected in the customary manner by pins 60^a. Associated with each cutter and supporting the same is a carrier block or plate-like member 61 which has depending lugs 61^a which are adapted to embrace the outer faces of the links and have openings therein through which the pivot pins of the chain links may pass, it being only necessary to provide slightly longer pins at the points where the carrier blocks 61 are to be connected. Each carrier block is provided with spaced parallel side flanges 61^b between which fit the cutter carriers 62 which have lateral flanges 62^a provided with elongated slots 62^b through which pass the securing screws 63. By loosening these screws each cutter carrier 62 may be adjusted lengthwise of the chain within the limits defined by the slots, whereby extreme accuracy of adjustment is possible. If a greater range of adjustment is necessary,

this may be effected by connecting the block 5 61 with the different pivots of the links, and it is, of course, obvious that links may be removed or added at will where it is necessary to lengthen or shorten the chain. As the form of cutter and manner of mounting it in the cutter carriers 62, is substantially the same as disclosed in the application above referred to, specific description thereof is deemed unnecessary.

Having thus described my invention, what I claim is:—

1. In a machine of the class described, the combination with a rotatable platen roll and a plurality of equally spaced apart connected cutters movable longitudinally of the roll and adapted to impinge thereagainst, of means for feeding the fabric to the roll including means for applying tension to the fabric.

2. In a machine of the class described, the combination with a rotatable platen roll and a plurality of equally spaced apart connected cutters movable longitudinally of the roll and adapted to impinge thereagainst, of means for feeding the fabric to the roll, including means for applying tension to the fabric, and means interposed between said feeding means and platen roll for spreading the fabric laterally.

3. In a machine of the class described, the combination with a rotatable platen roll and a plurality of spaced cutters movable longitudinally of the roll and adapted to impinge thereagainst, of means for feeding the fabric to the roll, including means for applying tension to the fabric, and means interposed between the feeding means and platen roll for brushing the opposite faces of the fabric.

4. In a machine of the class described, the combination with a rotatable platen roll and a plurality of spaced cutters movable longitudinally of the roll and adapted to impinge thereagainst, of a guide roll located on the opposite side of the platen roll around which the fabric is led prior to contact with said platen roll, whereby said fabric contacts with not less than one-half of the peripheral surface of the roll before reaching said cutters.

5. In a machine of the character described, the combination with a rotatable platen roll and a plurality of spaced cutters movable longitudinally of the roll and coacting therewith, with means for rotating said roll and moving said cutters at determined rates of speed, of a friction retarded supply roll, a puller roll adjacent the platen, around which the fabric passes, and means for driving said puller roll at a slower speed of rotation than that of the platen roll.

6. In a machine of the character described, the combination with a rotatable platen roll and a plurality of spaced cutters movable longitudinally of the roll and co-

acting therewith, with means for rotating said roll and moving said cutters at determined rates of speed, of a friction retarded supply roll, a puller roll adjacent the platen, around which the fabric passes, means for driving said puller roll at a slower speed of rotation than that of the platen roll, and a spreader roll interposed between said puller roll and supply roll and impinging against one face of the fabric.

7. In a machine of the class described, the combination with a rotatable platen roll and a plurality of spaced cutters movable longitudinally of the roll and adapted to impinge thereagainst, of means for feeding the fabric to the roll, including means for applying tension to the fabric, and means interposed between the feeding means and platen roll for brushing the opposite faces of the fabric, comprising a pair of oppositely extending arms located adjacent the opposite edges of the fabric, brushes carried by said arms and overlying opposite faces of the fabric, said arms being fulcrumed intermediate the brushes, and yieldable means tending to rotate said arms to press the brushes against the fabric.

8. In a machine of the character described, the combination with a rotatable platen roll and a plurality of spaced cutters movable longitudinally of the roll and coacting therewith, with means for rotating said roll and moving said cutters at determined rates of speed, of roll supply means for feeding uncut fabric to said platen roll, and means for securing the cut strips and winding them in roll form with an interposed liner.

9. In a machine of the character described, the combination with a rotatable platen roll and a plurality of spaced cutters movable longitudinally of the roll and coacting therewith, with means for rotating said roll and moving said cutters at determined rates of speed, and means for feeding fabric to said platen roll, of means for feeding a liner strip into contact with the cut strips in close proximity to the cutters, and means for winding up said liner with the cut strips in roll form.

10. In a machine of the character described, the combination with a rotatable platen roll and a plurality of spaced cutters movable longitudinally of the roll and coacting therewith, with means for rotating said roll and moving said cutters at determined rates of speed, and means for feeding fabric to said platen roll, of means for feeding a liner strip into contact with the cut strips in close proximity to the cutters, and means for winding up said liner with the cut strips in roll form, said liner feeding means including means whereby the liner is fed slightly faster than the surface speed of the platen roll, whereby the strips are ap-

plied to the liner with their edges in spaced relation.

11. In a machine of the class described, the combination with a platen drum and means for rotating it, of sprocket wheels at opposite ends of said drum, a sprocket chain passing around said sprocket wheels, and composed of detachable and interchangeable links, cutter carriers detachably connected 10 to said chain in spaced relation, cutters carried by said cutter carriers, and guide means for causing said cutters to travel in contact with the drum.

12. In a machine of the class described, 15 the combination with a platen drum and means for rotating it, of sprocket wheels at opposite ends of said drum, a sprocket chain passing around said sprocket wheels, and composed of pin connected links, guide 20 blocks having ears adapted for connection to said link pins, guides cooperating with said blocks, and cutter carriers adjustably connected to said guide blocks.

13. In a machine of the class described, 25 the combination, with a continuously driven

platens roll, and an endless chain of cutters arranged to impinge thereagainst longitudinally of the roll, of a frictionally retarded supply roll, of a spreader roll to which the fabric is led from the drum, a puller roll 30 over which the fabric is passed after leaving the spreader roll and whence it passes to the platen roll, and means for driving said puller roll at a slower speed than the platen roll. 35

14. In a machine of the class described, the combination, with a continuously driven platen roll, and an endless chain of cutters arranged to impinge thereagainst longitudinally of the roll, of a frictionally retarded supply roll, of a spreader roll to which the fabric is led from the drum, a puller roll 40 over which the fabric is passed after leaving the spreader roll and whence it passes to the platen roll, and means for driving said 45 puller roll at a slower speed than the platen roll, and means for driving the spreader roll at a faster speed than the puller roll.

In testimony whereof, I affix my signature.
JAMES W. BRUNDAGE.
